The ornamental design for the vehicular electro-optic mirror assembly, as shown and described.

DESCRIPTION

FIG. 1 is a front perspective view of a vehicular electro-optic mirror assembly in accordance with the present invention;

FIG. 2 is a rear perspective view of the vehicular electro-optic mirror assembly of FIG. 1;

FIG. 3 is a front elevation of the vehicular electro-optic mirror assembly of FIG. 1;

FIG. 4 is a rear elevation of the vehicular electro-optic mirror assembly of FIG. 1;

FIG. 5 is a side elevation of the vehicular electro-optic mirror assembly of FIG. 1;

FIG. 6 is an opposite side elevation of the vehicular electro-optic mirror assembly of FIG. 1;

FIG. 7 is a top plan view of the vehicular electro-optic mirror assembly of FIG. 1; and,

FIG. 8 is a bottom plan view of the vehicular electro-optic mirror assembly of FIG. 1.

The broken lines in the drawings are for illustrative purposes only and form no part of the claimed design.
